Charles N. Fairchild,

UNITED STATES PATENT OFFICE

CHARLES N. FAIRCHILD, OF NEW HAVEN, CONNECTICUT, ASSIGNOR TO FAIRCHILD LOCK CORPORATION, OF NEW YORK, N. Y., A CORPORATION OF DELAWARE

CAM-OPERATED IGNITION LOCK

Application filed May 25, 1927. Serial No. 194,195.

This invention relates to automobile locks and has for its principal object the provision of a lock in which the locking bolt and the ignition switch are both directly operated by a cam secured to the locking cylinder.

The lock in general is quite similar to that shown in my copending application Serial No. 172,113, filed March 2, 1927 and 10 retains all of the novel features of that lock but omits the direct cooperation between the locking bolt and the ignition switch stem.

In the drawings:—

Figure 1 is a face view of the lock.

15 Figure 2 is a side elevation partly broken away.

Figures 3 to 6 are views in section showing the parts in locked position, in unlocked position with the circuit broken, in running 20 position and in position just prior to pulling the key from the lock, respectively.

Figure 7 is a fragmentary view through the axes of the rock shaft and the plunger.

Figure 8 is a plan view of the blank from 25 which the slide 37 is made.

For convenience of description in the following specification the word "top" will be used to denote that portion of the device at which the switch box is located, but as 30 installed on the automobile, the device is arranged at an angle to both horizontal and vertical since the steering post casing and the cowl are each slanted, so that in strict accuracy the top of the lock housing is the 35 edge of the device formed by the meeting of the front face thru which the key is inserted, and the switch box attaching face.

The device in general consists of a housing 40 having a housing cap 11 each having a semi-cylindrical recess therein matching to form a complete cylindrical bore receiving the steering post casing. Each of the members, 10 and 11, is provided with a boss, that of the housing cap being solid and 45 usually an anvil 15 while the boss 16 of the main housing has a central cylindrical opening therein thru which slides the steering post locking bolt 17. The cap 11 is secured to the housing 10 in any desired manner 50 preferably by means of two one-way screws

18, the heads 19 of which seat about half way of the bores in the cap after the screws are driven home, and the remainder of these bores are then filled by plugs 20 driven in with a forced fit and finally smoothed flush 55 to the outside of the cap.

The switch box is preferably an insulating block 25 in which are located two resilient, arcuate contact pieces 27 and 28 spaced apart a convenient distance and which when 60 electrically connected close the ignition circuit. The wires leading to the switch box and connected to the contacts 27 and 28 preferably enter from the rear, that is behind the cowl board. The contact closing 65 element may be of any form desired as may the contacts themselves but the parts are here shown in a form that has been found very satisfactory in practice, the closing element being a metal cup 30 carried by and insulated from the stem 31 which is urged downwardly into open circuit position by a spring 32 confined between the disk 34 and a head 33 on the stem 31.

The locking bolt 17 has an enlarged circular head 40 freely slidable in its bore in the plug 41 but is not free to rotate since the head 40 carries a pin 43 projecting thru a slot in the plug 41 so as to lie in the path of the bolt raising cam 44 fast upon the inner or rear end of the cylinder of the spring-pressed plunger type lock, the barrel of which is denoted 46 in the drawings.

The barrel 46 of the lock is held in place in a tightly fitting bore of the housing by 85 means of a drive pin 47 which may, if desired, be slightly tapered and which, when once driven in, cannot be removed. The slightly larger counterbore of the lock barrel receiving bore in the housing is closed 90 by a cylindrical cap 48 also held in place by the pin 47. A spring 49 engages the head 40 of the locking bolt 17 and constantly tends to shoot the bolt 17 into locking position.

The slide 35 is formed from a flat sheet of metal having in one end a slot 36 which snugly embraces a reduced portion of the stem 31. The body or guiding portion 37 of the slide fits in a slot 38 in the plug 41 100

and has a downwardly projecting portion 39 which is engaged by the lifting cam 44 of the lock 46 so that the stem 31 and consequently the circuit closing cup 30 is lifted 5 solely and directly by the lifting cam.

Proper movement of the cylinder of the lock by means of its key 50 turns the cam 44 so that the lug or pin 43 on the head 40 rides up the spiral arc or curve 51 to the 10 point 52 at which time the spring 49 is compressed, the bolt 17 entirely withdrawn from locking engagement, and contact is made between the cam 44 and the slide 35 but the latter is not lifted to close the ignition circuit as will be seen by Figure 4 showing the parts in this 215° position, i. e., just prior to turning to the running position shown in Figure 5.

There are three notches in the edge of the 20 cam 44, namely, a notch 60 which may be a one-way notch as shown or may be a two-way notch and which receives the cylindrical pin 43 which acts in this position as a detent to hold the parts in "third position" 25 when the key can be removed leaving the steering post unlocked and the ignition off as once was required by police regulations of a few cities, a notch 61 which must be a one-way notch in which the pin 43 is engaged at 215° just beyond third position, and a detent notch 62 which is engaged by the pin 43 at running position at 270° as shown in Figure 5. The key can readily turn the lock from 215° to 270° and 270° to 30 215°, from 0° to 180° and may from 180° to 0° but once the device has been advanced to the 215° position shown in Figure 4 the one-way notch 61 prevents its return to "third position" which is so named because 35 it was the third position to be invented. Considered merely in terms of revolution the so-called third position is the first position which is met after the key is inserted in the lock.

40 70 is a rock shaft to the front of which on the outside of the housing is a lever 71 having a downturned arm 72 and an upturned arm 73. In the 0° position shown in Figure 1 the downturned arm 72 just permits entry of the key into its key hole and the upturned arm 73 is entirely clear of the circular opening 75 in the cylindrical cap 43 which, it will be noted, has a slot 76 permitting travel of the downturned arm 72. 45 In running position the cam 80 has moved the finger or arm 72 so far that the edge 79 of the lever 71 has engaged against the shoulder 82 of the plunger 83 and the key in this position cannot be turned in clockwise direction because of the engagement of its edge with the upturned end 73 but can be turned counter clockwise back to 215°. When the plunger has been depressed and the stem portion 85 is engaged by the edge 50 79, the edge of the key is in contact with

the upturned end 73. The plunger is held depressed by the lever 71 and the binding action of the lever prevents further movement of the key in a clockwise direction. It will be remembered the key is now in position to be withdrawn from the lock and hence need not be turned further in clockwise direction. If the key is now withdrawn the locking bolt 17 will rock the rock shaft 70 and with it the lever 71 and will move to locking position under urge of its spring 49 and as soon as the plunger 83 is released its spring 87 will return it to normal position.

55 Referring particularly to Figure 6 which shows the locking bolt withdrawn and the ignition circuit closed but with the lock cylinder turned to the 360° position at which the key can be withdrawn, the pin 43 which extends laterally from the locking bolt head is free to move to locking position as far as the cam is concerned but the locking bolt is held in unlocked position by the rock shaft 70 and nothing can happen until the key is withdrawn. As shown in Figure 6 the slide 35 has moved slightly downward but only a small fraction of the distance which is required to break the ignition circuit. The downward movement of the slide 35 when freed from the lock cylinder lifting cam is arrested by engagement of the slide with the locking bolt lateral pin 43 and the ignition circuit can only be broken when the locking bolt moves downward whereupon the slide 60 under the urge of spring 32 will snap down following the bolt and breaking the ignition circuit.

65 The end of the rock shaft is milled away as at 90 so as to engage in a notch cut in the steering post locking bolt 17 consisting of a plurality of communicating grooves such as 91 and 92 meeting in cusps 93 and 94. In driving position, the key has been turned thru 270°, the ignition is on and the steering gear is unlocked but the key cannot 70 be removed as its forward movement is stopped indirectly by the push button or plunger 83. The locking bolt 17 is held retracted by the steel lifting cam 44 and also by the steel safety shaft 70 herein 75 termed the rock shaft. The key however, from this position can be turned backward to the 215° position illustrated in Figure 4. In this position the ignition is off but the steering post is unlocked and the automobile 80 can be steered. The key can be turned forward to the position in Fig. 5 but cannot be turned backward to third position at 180° as previously described and the key cannot 85 be removed. This provision allows a driver to turn his ignition off and on at will under such conditions as may seem advisable to him and there is no possibility of the steering post becoming locked as even if some 90 of the parts failed the double safety would 95

insure against involuntary locking and absent-minded or accidental locking is prevented because two separate actions are required to move forward to Figure 6 position, one, the pressing in of the plunger and the other the simultaneous turning of the key.

What I claim is:—

1. In a key operated coincidental lock, 10 a locking bolt, a cam operated ignition switch, means for holding the locking bolt in unlocked position until the key is withdrawn from the lock, and means carried by the locking bolt for holding the ignition 15 switch in circuit closing position when said switch is freed from its cam, whereby the ignition circuit may not be broken until the key is withdrawn from the lock.

2. In a key operated coincidental lock, a locking bolt, a cam operated ignition switch, means for holding the locking bolt in unlocked position until the key is withdrawn from the lock, and means laterally projecting from said bolt for holding the ignition 25 switch in circuit closing position when said ignition switch has otherwise been freed by movement of its cam.

3. In a coincidental lock, a locking bolt, an ignition switch contact, a cam, and means 30 operated by said cam for moving the bolt to unlocked position and for independently moving said contact to ignition circuit closing position.

4. In a coincidental lock, a sliding bolt, a 35 stem carrying an ignition circuit contact, and means for moving said bolt and said stem in the same direction but constantly out of contact with each other into unlocked position and circuit closing position, respectively.

5. In a key operated revolving cylinder coincidental lock, a locking bolt, an ignition make and break contact, and means for first engaging said bolt and for later engaging said contact after further angular travel of the lock cylinder.

6. In an ignition switch, a plurality of contacts, means for resiliently separating said contacts, a lock cylinder, a cam secured 50 to said cylinder, and means engaging one of said contacts and lying in the path of the cam whereby rotation of the cam will bring the two contacts into engagement thereby closing the ignition circuit.

7. In an ignition switch, a plurality of contacts, a third contact for bridging said first mentioned contacts to close the ignition circuit, a stem projecting from the third contact, spring means surrounding said stem resiliently to hold the third contact from bridging position, a member laterally extending from the stem and then bent at an angle, and a cam for engaging the laterally extending member to raise the third contact against the action of its spring.

8. The device of claim 7 including means for holding the laterally extending member in bridging position after said member is freed from its cam.

9. In an ignition switch, a housing having a bore of two diameters, a disk positioned against the shoulder between the two bores, a hollow cylindrical casing fitting the larger diameter bore of the housing and against said disk, a stem slidably mounted 70 in the housing and guided by one end of the housing and by the disk, said stem extending on both sides of the disk and projecting into the central bore of the casing, a sliding bracket secured to said stem and guided by said casing in its periphery, and cam means engaging an extremity of said guided bracket for moving said stem.

10. In a coincidental lock, a housing having a bore therethru of three diameters, an ignition switch stem slidable in the smallest bore, a head on said stem, a disk positioned against the shoulder between the intermediate and larger bore, a casing fitting the larger bore, a bolt slidable within the casing, a spring between the disk and head, key operated means for moving the bolt and stem in one direction, and means for moving the bolt in the opposite direction independently of the movement of the stem.

11. In a coincidental lock, a housing having a bore of three diameters, an ignition switch stem slidable in the smaller diameter, a disk against the shoulder between the intermediate and larger diameter bores, a 100 plug having a two diameter bore therethru fitting in the larger bore of the housing and having a cylindrical extension projecting beyond the housing to form a boss to be received in the steering post casing, a bolt 105 slidable in the smaller bore of the plug, a head integral with the bolt and sliding in the larger bore of the plug coaxial with the ignition switch stem, and means for raising the bolt and stem while holding 110 them out of contract with each other.

12. In a key operated coincidental lock, a locking bolt, a cam operated ignition switch, means for positively holding the locking bolt in unlocked position until the key is withdrawn from the lock, and means laterally projecting from said bolt for holding the ignition switch in circuit closing position when said ignition switch has otherwise been freed by movement of its cam.

13. In an ignition switch, a plurality of contacts, a third contact for bridging said first mentioned contacts to close the ignition circuit, a stem projecting from the third contact, spring means surrounding said stem resiliently to hold the third contact from bridging position, a member laterally extending from the stem and then bent at right angles into substantial parallelism with the axis of the stem, and a cam for en- 125 130

gaging the laterally extending member to raise the third contact against the action of its spring.

14. In a lock, a cam having two notches and a one-way notch between them, a locking member having a stud in engagement with the cam and adapted to rest in said notches, a sliding member movable by said cam, and means for holding the stud out of contact with the cam and the sliding member against movement.

In testimony whereof I affix my signature.

CHARLES N. FAIRCHILD.
